UNITED STATES PATENT OFFICE.

FREDERICK CHARLES SCOTT, OF DETROIT, MICHIGAN.

HOSE-CLAMP.

1,135,059.

Specification of Letters Patent. Patented Apr. 13, 1915.

Application filed July 20, 1914. Serial No. 852,078.

To all whom it may concern:

Be it known that I, FREDERICK C. SCOTT, a British subject, residing at Detroit, in the county of Wayne and State of Michigan, have invented a new and useful Hose-Clamp, of which the following is a specification.

The invention relates to improvements in hose clamps.

10 The object of the present invention is to improve the construction of hose clamps and to provide a simple, practical, and efficient hose clamp, of strong and durable construction, consisting of a single strip of sheet metal and adapted to be rolled into shape without twisting it, and of being opened sufficiently to enable it to be readily applied to a hose without liability of the clamp opening or untwisting entirely.

20 A further object of the invention is to reduce the cost of hose clamps of this character by enabling the same to be constructed of light material, without impairing their strength or causing them to buckle 25 or crimp at the point where the pressure is applied for drawing the terminals of the strip inwardly.

With these and other objects in view the invention consists in the construction and 30 novel combination of parts hereinafter fully described, illustrated in the accompanying drawing, and pointed out in the claims hereby appended, it being understood that various changes in the form, proportion, 35 size and minor details of construction, within the scope of the claims, may be resorted to without departing from the spirit or sacrificing any of the advantages of the invention.

40 In the drawing: Figure 1 is a perspective view of a hose clamp constructed in accordance with this invention. Fig. 2 is a sectional view of the same. Fig. 3 is a perspective view of the metallic strip rolled to form 45 a hose clamp and illustrating the means for limiting the opening or uncoiling of the strip. Fig. 4 is a plan view of the blank from which the strip is formed.

Like numerals of reference designate corresponding parts in all the figures of the drawing.

In the accompanying drawing, in which is illustrated the preferred embodiment of the invention, 1 designates a strip of sheet 55 metal or other suitable material provided at a point intermediate of its ends at one

side of the center with an enlargement 2 having a longitudinal slot 3 of a width to permit the strip to pass through it without twisting or turning to enable the strip to be 60 partially coiled to present a continuous surface to a hose or other flexible tube and to permit the terminal portions to be drawn together around the hose engaging portion of the strip. The terminal portions 4 of the blank are laterally enlarged and tapered, forming substantially diamond shaped portions which are shaped by stamping or pressing to provide terminal ears 5 and webs or flanges 6 arranged at opposite sides of the 70 strip and connecting the ears 5 with the side portions of the strip. In the formation of the ears and flanges, the approximately diamond shaped terminal portions are bent on the dotted lines *a*, *b* shown in Fig. 4 of 75 the drawing. The ears and flanges or webs of one end of the strip are adapted to pass through the slot 3 and the terminals of the strip are adjustably connected by means of a bolt 7 provided at one end with a head 8 and threaded at the other end to receive a nut 9. The ears are provided with openings 10 for the passage of the bolt, and one of the ears is engaged by the head 8 of the bolt and the other end 9, which fits between the 80 side flanges or webs of such end, and is thereby held against rotary movement when the bolt is turned to draw the ends of the strip together for applying the desired pressure to the hose or other tube. In order to facilitate applying the clamp to a hose, the strip is provided adjacent to one of its ends with laterally projecting lugs 11 formed integral with the strip and adapted to be bent up at right angles to the said strip to enable 85 them to pass through the slot 3, and after the said lugs have been passed through the slot, they are then bent outwardly into the plane of the adjacent portion of the strip, and as they form a laterally enlarged portion of greater width than the slot 3, it will 90 be apparent that they will prevent the adjacent terminal portion from being drawn backwardly through the slot. The laterally 95 projecting lugs 11, which have straight inner transverse edges 12, preferably extend to the side edges of the slotted enlargement 2. When it is desired to apply the clamp to a hose, the bolt may be removed and the 100 resilient strip will bend out to approximately the position shown in Fig. 3 of the drawing 105 and will be limited in such opening move-

ment, so that there will be no danger of the strip entirely uncoiling. After the coiled strip has been placed around the hose, the ends of the strip may be drawn toward each other and connected by the bolt, which will enable the hose to be clamped with the desired pressure. The strip is also provided with an imperforate enlargement 13, projecting at the side edges of the strip and being of a length to extend across the space between the ears when the nut is at the outer end of the bolt and the clamp is adjusted to its greatest diameter. This enlargement 13, which lies beneath the bolt and stiffens the clamp between the connected terminals of the strip, will enable the terminals to be drawn together by the bolt to apply the desired pressure to the hose without liability of causing the strip to buckle or bend beneath the bolt. This will maintain an even pressure upon the hose and by widening the strip at this point, the clamp may be constructed of much lighter material than otherwise. This will lessen the cost of manufacture without affecting the strength of the device.

What is claimed is:—

1. A clamp of the class described consisting of a single strip of metal provided with a longitudinal slot of a size to permit one

end of the strip to pass through it without twisting, the end of the strip which is passed through the slot being provided with a lateral enlargement forming a stop and adapted to be bent inwardly so as to pass through the said slot, said enlargement, when bent outward, forming a stop for engaging the slotted portion of the strip to limit the opening movement of the clamp, and means for adjustably connecting the terminals of the strip. 35

2. A clamp of the class described consisting of a single strip of metal provided with a longitudinal slot of a size to permit one end of the strip to pass through it without twisting, the end of the strip which is passed through the slot being provided with a pair of laterally projecting lugs adapted to be bent inwardly so as to pass through the slot, said lugs, when bent outwardly, forming stops for limiting the opening movement of the clamp, and means for adjustably connecting the terminals of the strip. 45

In testimony that I claim the foregoing as my own, I have hereto affixed my signature in the presence of two witnesses.

FREDERICK CHARLES SCOTT.
